(57) **CLAIM**

The ornamental design for a yoked headgear, as shown and described.

DESCRIPTION

FIG. 1 is a perspective illustration of a yoked headgear according to our new ornamental design;

FIG. 2 is a front view thereof;

FIG. 3 is a rear view thereof; and,

FIG. 4 is a right side view thereof.

The dash-dot-dash lines in the drawing figures are included to show unclaimed portions only and form no part of the claimed design.

The use of stippled shading and line shading is used to indicate contrasting materials.

The dotted lines represent the border between claimed and unclaimed subject matter and form no part of the claimed design.
